HEAD FLOWING FLUID LIFT

Application filed May 26, 1927. Serial No. 194,369.

This invention relates to fluid lifts especially adapted for use in wells.

An important object of the invention is to provide a head flowing fluid lift having means whereby the air or gas inlet valve may be adjusted preparatory to the installation of the lift so that the same may be moved to air or gas inlet position only as a result of the accumulation of a predetermined volume of oil or other fluid in the tubing whereby the well may be flowed at the most advantageous intervals and the supply of lifting medium conserved.

Another and equally important object is to provide a fluid lift in which the intimate mingling of the lifting medium, be it compressed air or gas, with the column of oil being lifted is avoided whereby cutting of the oil and lowering of the gravity thereof is reduced to a minimum.

The invention forming the subject of this application also embodies novel means by which the oil or other product of the well between the tubing and the casing during or subsequent to the installation of the improved lift may be expeditiously pumped off to allow of the most efficient use of the compressed air or gas as a lifting medium.

Other objects and advantages will be apparent during the course of the following description.

In the accompanying drawings forming a part of this application and in which like numerals are employed to designate like parts throughout the same,

Figures 1 and 1a are vertical sectional views through the improved pump in position to admit oil to the tubing and to exclude the lifting medium,

Figure 2 is a fragmentary vertical sectional view through the pump in position to admit a lifting medium and to exclude oil,

Figure 3 is a side elevation of a sleeve valve embodied in the invention,

Figures 4 and 4a are vertical sectional views through a modification of the invention.

In the drawings the numeral 5 designates a well casing, the lower portion of which is provided with the usual shoe 6 adapted

to be positioned on the cap rock of the producing stratum in accordance with standard practice.

The invention forming the subject of this application is adapted to be attached to a tubing 7 through the medium of a coupling 8, to the lower portion of which the casing 9 is connected. Figure 1 clearly illustrates that the casing is in the nature of a cylinder having the upper portion thereof divided and the ends thus formed connected to an annular member 10.

The lower terminal of the cylinder 9 has connection with the upper annulus or end member 11 of a more or less conventional packer 12. With reference to Figure 1 it will be seen that the body of the packer 12 is expansible and is adapted to have fluid tight contact with the wall of the well casing to seal off the annular space between the tubing and well casing above the packer from the space below. The lower end member or annulus 14 of the packer is slidably mounted on a nipple 16 incorporated in the main inlet conduit for the oil and the parts 14 and 16 are provided with flanges 18 and 20 respectively for contact during the descent of the fluid lift into the well. It is not new, but it might be explained that when the perforated portion 24 of the inlet conduit is engaged with the bottom of the well the annulus or upper end member 11 carried by the nipple 16 will continue to descend to expand the packer into fluid tight contact with the well casing. Thus a seal is established at this point.

The annular space between the tubing and the well casing constitutes a chamber or reservoir for a lifting medium, such as compressed air or gas, which comes into lifting relation to the tubing fluid by entering through ports 26 and 28 and by passing through check valves 30. In explaining this, attention is invited to Figure 1 which illustrates that a sleeve valve 32 is mounted on the main fluid inlet member 33 within the cylinder or casing 9 and is provided with ports 34 adapted to be brought into register with the ports 26 and 28 to permit of the flow of the lifting medium, such as com-

pressed air or gas, from the well casing into the tubing.

Continued reference to Figure 1 will show that the sleeve valve 32 is urged down to closed position by a suitably stout spring 36 confined between the annular member 10 and a washer 38 on the upper end of the sleeve valve.

It will be seen that after the intentional breaking of a knockout disk 40 in a manner and for a purpose to be hereinafter described, oil or other product of the well may rise in the tubing and exert a pressure on the under side of the sleeve valve 32 sufficient to overcome the pressure of the spring 36 whereupon the valve is moved to the open position illustrated in Figure 2. In this connection reference is had to Figure 1a which illustrates a gas relief port 42 in the perforated portion 24 of the inlet conduit for the oil. This figure also illustrates a tubular member 43 extending entirely through the packer so that the pressure of the column of fluid within the tubing may act on the under side of the sleeve valve to raise the sleeve valve to open position when this pressure is sufficient to overcome the pressure of the spring 36. In other words, the pressure of the tubing fluid is transmitted through the port 42 and the tubular member 43 to the underside of the sleeve valve 32 whereby the accumulation of a predetermined volume of oil in the tubing will operate the sleeve valve.

It is here noted that the space exteriorly of the oil inlet conduit between the port 42 and the lower end of the sleeve valve will be occupied by trapped gas, but this gas will not in any way impair the operation of the pump as the pressure of the fluid may act through this gas quite as effectively as if the column of fluid had direct contact with the sleeve valve.

Attention is again invited to Figure 1 which illustrates that the compression of the spring 36 under the influence of the pressure of the column of fluid in the tubing is limited by a stop sleeve 45 disposed within the cylinder 9 and between the member 10 and the washer 38. It is possible to vary the effective pressure of the spring 36 by adding or removing washers 38 or the equivalent thereof. Also stouter or lighter springs may be employed. In this connection it is observed that the pressure of the spring 36 may be adjusted preparatory to the installation of the improved fluid lift in a well so that a minimum pressure on the producing stratum may be maintained. In explaining this it is pointed out that the tension of the spring 38 may be adjusted to yield under a predetermined hydrostatic pressure so that when the weight of the column of fluid in the tubing exceeds this the sleeve valve will be moved to open position whereupon compressed air or gas may enter the tubing and elevate the column of fluid above. As the pressure within the tub-

ing drops as a result of the flow of fluid therein, the pressure tending to hold the valve in open position is correspondingly reduced with the result that the spring will return the valve to closed position.

The sleeve valve 32 is provided on the outer side thereof with sets 46, 47 and 48 of spaced rings, cups or the like having fluid tight contact with the cylinder 9 to avoid leakage of the lifting fluid such as compressed air or gas. When the sleeve valve is in closed position as suggested in Figure 1 the sets of rings 46 and 47 will be positioned at opposite sides of the ports 26. The location of the rings 46 and 47 at opposite sides of the ports 26 when the sleeve valve is closed is assured by a stop sleeve 44 mounted in the lower portion of the cylinder.

When the valve 32 is in open position the registration of the ports 34 with the ports 26 and 28 and the location of the rings 47 and 48 at opposite sides of the ports 26 is assured by the sleeve 45 between the upper end of the sleeve valve and the member 10.

In carrying out the invention the conduits 33 and 55 are provided at opposite sides of the ports 28 with rings 68 and 69 which actively cooperate with the rings on the outer side of the sleeve valve in avoiding leakage.

Attention is invited to Figure 2 which illustrates that the oil inlet 33 is provided with additional rings 70 by which fluid of any nature which may be beneath the sleeve valve 32 is prevented from working its way between the sleeve valve and the conduit.

In assembling the improved pump for use in a well the frangible knockout disk 40 is secured above the perforated portion 24 of the inlet conduit and below the packer to prevent the premature admission of oil or the like into the tubing by way of the inlet portion 24, which will, of course, later function as the sole inlet for the products of the well. During the introduction of the improved fluid lift into the well the packer 12 is, of course, in its nonexpanded position with the result that the oil already in the well casing will pass about the surface of the packer and collect between the tubing and the well casing. The pressure of this fluid between the tubing and well casing will manifest itself against the under side of the sleeve valve 32 and raise the sleeve valve to open position even before the packer is seated at the proper point in the well casing. When the sleeve valve 32 is thus moved to open position the oil or other product of the well between the tubing and the well casing above will enter the tubing by way of the ports 26, 34 and 28 and the conduit 55 and the valves 30. Of course the tubing and casing fluids will assume the same level and a liner working barrel may be lowered through the tubing and the lower portion thereof engaged with the annular seat 56 in the upper portion of

the coupling 8, after which the working barrel, which may be of standard design, is operated from the surface to pump out the fluid trapped at the time the packer was set. The action of the working barrel is substantially aided by compressed air or gas acting on the head of oil or the like between the tubing and the well casing. In other words, gas from the well being operated or gas or compressed air from an outside source is confined in the casing above the liquid level therein and will exert a pressure on the head of casing liquid to aid the working barrel in lifting the liquid through the tubing. In this manner the oil originally between the tubing and the well casing is recovered, after which the working barrel is withdrawn to the surface.

A striking element such as a heavy bolt is now dropped through the tubing to knock out the frangible disk 40 so that the well may, if possible, flow under the natural pressure thereof. When the well ceases to flow under the natural pressure thereof for any reason the compressed air or gas may be turned on and the well livened up after which it may flow for a period under its own pressure. During the application of compressed air or gas the well may be flowed by heads which is considered the most advisable or the fluid may be sprayed by maintaining a back pressure on the tubing fluid sufficient to hold the valve 32 in the position illustrated in Figure 2. It is well known and it is not uncommon in the industry to maintain a back pressure on the well by the employment of a choke at the surface and by means of which the fluid conducting member is restricted.

When the well has ceased to flow under its own pressure a standing valve 57 may be dropped through the tubing into a seat at the upper portion of the conduit 66 so that during the subsequent head flowing of the well the lifting medium is prevented from exerting a back pressure on the producing stratum.

As previously suggested the head flowing of the well is accomplished by the pressure exerted on the under side of the sleeve valve 32 which moves the valve to open position illustrated in Figure 2 whereupon compressed air or gas is admitted to lift the column of fluid to the surface. When the lifting medium discharges a portion of the column of fluid from the tubing the load on the lifting medium is substantially lightened so that the lifting medium, which may be in the nature of compressed air or gas, is used expansively to accelerate the ascent of the remaining portion of the column of fluid.

As the compressed air or gas within the tubing expands the tubing pressure will drop with the result that additional oil may enter the tubing preparatory to the next flowing of the well.

The presence of the one-way valves 30 prevents sand which may settle from the column of fluid from entering the conduit 55 and possibly freezing or fowling the rings or cups or causing excessive wear of the sleeve valve. Another very important function of the one-way valves 30 is to prevent the escape of oil or the like through the improved fluid lift when the well is flowing naturally. Furthermore, if for any reason the supply of compressed air or gas is interrupted and the tubing pressure becomes sufficient to move the valve 32 to the open position illustrated in Figure 2 the valves 30 will prevent the oil in the tubing from traveling out through the ports 34 and associated ports into the space between the tubing and the casing above the packer.

It might be noted that the sleeve valve 32 is held against turning by a key 87 carried by the lower end of the sleeve valve and received in a longitudinal groove or key-way 88 in the inlet 33. Of course any other mechanical expedient may be employed to hold the sleeve valve against turning.

In the form of invention illustrated in Figures 4 and 4a the tubing is designated by the numeral 100 while the casing or outer cylinder of the improved fluid lift is designated by the numeral 101. The cylinder 101 cooperates with an inner cylinder 102 in the formation of an annular chamber for the reception of a sleeve valve 103. Figure 4 clearly illustrates that a compression chamber 99 is provided by the cylinder 101, the piston 103 and the upper bushing 106 and that this compression chamber may be supplied with air by way of a valve 104.

In carrying out this form of invention air under pressure is forced into the chamber 99 through the valve 104 and by reason of the fluid tight contact between the parts shown in Figure 4 the air thus introduced into the chamber 99 is of substantially constant volume to act in the nature of a spring for returning the sleeve valve 103 to closed position when hydrostatic pressure drops below a predetermined point.

The sleeve valve 103 is provided with radial ports 108 adapted for registration with ports 109 and 110 in the cylinders 101 and 102 respectively and it is through these ports that a lifting medium such as compressed air or gas may enter from the casing and assume lifting relation to the fluid accumulated in the tubing. Particular attention is invited to Figure 4a which illustrates that the lower portion of the cylinder 102 is provided with a suitable number of ports 111 by which tubing pressure may assert itself against the under side of the sleeve valve to move the sleeve valve upwardly to air or gas inlet position.

It is important to observe that the upward movement of the sleeve valve to gas

or air inlet position in response to an increase in tubing pressure is resisted not only by the pressure of the air within the chamber 99, but by a spring catch 121 which is engaged with the shoulder of a dog 120. In other words, when the laterally projecting terminal portion of the spring catch 121 is engaged with the shoulder of the dog 120 the pressure of the column of oil in the tubing must overcome the restraining influence of the spring 121 combined with the pressure exerted by the air in the chamber 99 before the sleeve valve may be moved to inlet position. However, when the dog is released from engagement with the spring catch 121 the tubing pressure being so much greater than the pressure within the chamber 99 will quickly move the sleeve valve to open position. The dog 120 is connected to the lower end of the sleeve valve 103 by suitable means such as a threaded stem 118.

When the piston is thus moved to open position as shown in Figure 4 a second dog 125 carried by the upper portion of the sleeve 25 valve is engaged with the laterally projecting terminal portion of a spring catch 124 to hold the sleeve valve in inlet position even after the tubing pressure drops. Of course a drop in the tubing pressure to a point substantially below the pressure exerted by the air within the chamber 99 will result in the disengagement of the dog from the spring 124 whereupon the sleeve valve is returned to air excluding position by the air confined 30 under pressure within the chamber 99.

During the admission of air or gas to the tubing to lift the column of oil therein a standing valve 144 in the inlet member 141 remains closed so as to prevent an excessive 40 back pressure on the producing sands by the air or gas. A suitable perforated anchor 143 is located at the lower portion of the inlet member 141.

The improved fluid lift contemplates the 45 employment of a packer 140 directly beneath the lift to provide a seal at this point whereby the lifting medium may be supplied to the fluid lift by way of the casing without creating a back pressure on the sands.

Having thus described the invention what 50 is claimed is:

1. In a fluid lift for wells, a valve casing having an inlet for the admission of a fluid lifting medium, a longitudinally movable valve within said casing and having a port to register with said inlet, means urging said valve to an extreme position, a conduit extending through said valve and adapted for the passage of the products of the well, a tubing 55 receiving the products of the well from said conduit and receiving the lifting medium from said casing, and a check valve between said valve casing and said tubing.

2. A head lift flowing device for wells comprising a casing, a tubing for connection with

the casing, a valve within said casing and having means controlling the admission of a fluid lifting medium to the tubing, a conduit for the passage of a fluid lifting medium extending partly through said valve, and a 70 check valve between said first-named valve and said tubing and inhibiting retrograde movement of fluid in said tubing.

3. A head lift flowing device for wells comprising a casing, a tubing for connection with the casing, a valve within said casing and having means controlling the admission of a fluid lifting medium to the tubing, a liquid conduit extending partly through said first-named valve and adapted for communication with said tubing, a check valve between said first-named valve and said tubing, there being means whereby the tubing pressure may urge said first-named valve to open position. 75

4. A head lift flowing device for wells comprising a casing, a tubing for connection with the casing, a valve controlling the admission of a fluid lifting medium to the tubing, a lifting medium conduit extending partly through said valve and adapted for communication with said tubing, a check valve between said first-named valve and said tubing, there being means whereby hydrostatic pressure may urge said valve to open position, and means urging said first-named valve to closed 80 position against hydrostatic pressure. 85

5. A head lift flowing device for wells comprising a valve having means to control a lifting medium, means urging said valve to closed position, a conduit extending partly through said valve and adapted for the passage of a lifting medium, a second conduit within the first-named conduit and adapted for the passage of the products of a well, and separate control devices at the outlets from 90 said first and second named conduits. 100

6. In a fluid lift, a valve having means to control a lifting medium, a spring urging said valve to closed position, a conduit extending through said valve and adapted for the passage of a lifting medium, a second conduit within the first-named conduit and adapted for the passage of the products of a well, and a one-way valve at the outlet of 105 said second-named conduit. 110

7. A head lift flowing device comprising a valve having means to control a lifting medium, a conduit extending through said valve and adapted for the passage of a lifting medium, a second conduit within the first-named conduit and adapted for the passage of the products of a well, and a one-way valve associated with said second-named conduit, there being means whereby hydrostatic 120 pressure may act on said valve to urge the same to open position to admit a lifting medium. 125

8. A head lift flowing device comprising inner and outer tubular members having ports, the inner tubular member defining a 130

conduit for a lifting medium, a sleeve valve between said tubular members and having a port adapted for registration with said first-named ports, an inlet member in communication with one of said tubular members and adapted for the passage of the products of a well, there being means whereby hydrostatic pressure in said inlet member is transmitted to said valve to urge the same to open position, and a one-way valve in the path of travel of the fluid from the well.

9. In a fluid lift for wells, inner and outer tubular members having ports for the passage of a lifting medium into lifting relation to the products of the well, a valve between said tubular members and having a port adapted for registration with said first-named ports, a packer associated with one of said tubular members and having a passage whereby hydrostatic pressure may act on said valve, and a spring urging said valve in the direction opposite the direction it is urged by hydrostatic pressure and adapted to yield under hydrostatic pressure on said 25 valve, one of said tubular members constituting a conduit for the movement of the products of the well, and a valve in the line of travel of the products of the well.

10. In a fluid lift for wells, inner and outer tubular members having ports for the passage of a lifting medium into lifting relation to the products of the well, a valve between said tubular members and controlling the ports therein, a packer associated 35 with one of said tubular members and having a passage whereby hydrostatic pressure may act on said valve, a spring urging said valve in the direction opposite the direction it is urged by hydrostatic pressure and adapted to yield under hydrostatic pressure on 40 said valve, one of said tubular members constituting a conduit for the movement of the products of the well, and stop elements limiting movement of said valve.

45 11. In a fluid lift for wells, inner and outer tubular members having ports for the movement of a lifting medium into lifting relation to the products of the well, a sleeve valve between said inner and outer tubular members and controlling said ports, there being means whereby hydrostatic pressure may act on said valve, said inner conduit having separate passages for the flow of the products of the well and a lifting medium, and means 50 urging said sleeve valve to an extreme position against hydrostatic pressure.

55 12. A head lift flowing device comprising a casing having inner and outer tubular members, a tubing having connection with said casing, a sleeve valve between said inner and outer tubular members and having means to admit a lifting medium to the tubing, said casing being provided with a one-way valve between said first-named valve and the tubing, there being means controlling the move- 60

ment of said sleeve valve by variations in hydrostatic pressure, said inner tubular member being adapted for the flow of the products of a well and having communication with said tubing, and a one-way valve in the line of flow of the products of the well. 70

13. A head flowing fluid lift for wells comprising a tubing, a valve having means to admit a lifting medium to the well tubing and being exposed to and moved to inlet position by hydrostatic pressure, an inlet member adapted for communication with the producing stratum of the well, and a second valve associated with the inlet member and exposed and adapted to be closed by the lifting medium in the tubing whereby the producing stratum is maintained free of the lifting medium. 75

14. In a fluid lift for wells, a conduit adapted for the passage of well liquid, a valve 80 casing having means to admit a lifting medium into lifting relation to liquid in said conduit, a valve controlling said means and being exposed to and movable in one direction under the influence of hydrostatic pressure, and a check valve in the path of travel of the lifting medium between the first-named valve and the liquid in said conduit. 85

15. In a fluid lift, a casing having spaced interfitting conduits defining a passage for the products of a well and a separate passage for a lifting medium, there being means to admit a lifting medium to the passage therefor, a pressure actuated valve within said casing controlling said means for the admission 90 of the lifting medium to the passage therefor, and a one-way valve at the outlet from said passage for said lifting medium. 95

16. In a fluid lift, a casing having spaced interfitting conduits defining a passage for the products of a well and a separate passage for a lifting medium, there being means to admit a lifting medium to the passage therefor a valve controlling said means for the admission of the lifting medium and being exposed to and responsive to hydrostatic pressure, and separate valves at the outlets to said passages. 100 105

17. In a fluid lift for wells the combination of a casing adapted for the flow of a lifting medium, a tubing within the casing and adapted for the passage of the products of a well and the lifting medium, a valve controlling communication between the tubing and the casing, and a packer between the tubing 110 and the casing at a point below said valve, there being means extending through the packer and exposing said valve to hydrostatic pressure. 120

In testimony whereof I affix my signature. 115
JOHN PENROD. 125
